*SNUFEER AND METHOD OF SNUFFING

Ward M. Irvin, Battle Creek, Mich.

Application March 7, 1942, Serial No. 433,749

5. Claims. (Cl. 131—256)

The present invention relates broadly to snuffers, and in its specific phases to a method and apparatus for snuffing lighted cigarettes.

The exigencies of war conditions make highly desirable the conservation of paper and the economical use of tobacco in order to hold down expense and reduce the drain on paper supplies. A marked saving along this line can be accomplished by smokers snuffing out their partially burned cigarettes, instead of throwing them away, and then resmoking same later. This procedure, however, is not without difficulties, since if the snuffing is done in a closed end tube, it is difficult to clean out the ashes, bits of tobacco, et cetera, which normally accumulate in the bottom of same. Moreover if a cigarette is snuffed in this manner, the smoke and fumes from the burning end of the cigarette are pocketed and saturate the tobacco in the remaining portion of the cigarette, a thing which destroys the original fresh taste and aroma of same. Where the bore of the snuffer is considerably larger than the cigarette, this permits at least limited smouldering which again is destructive of the taste and aroma, and also tends to dry out the cigarette so that upon resmoking same, it bites the tongue. Any attempt to snuff the cigarette in a closed compartment acts to seal in the ashes, smoke, and undesirable odors which again taint the cigarette. These shortcomings and disadvantages of the prior art lead to the discovery and development of the present invention.

Accordingly among the objects of the present invention is the provision of a cigarette snuffer wherein the cigarette closely fits the bore of same so that a minimum amount of air is available to support combustion and this air is largely forced out of the snuffer due to movement of the cigarette thereinto as well as by means of smoke and vapor expansion caused by heat from the lighted or hot end of the cigarette. This produces an almost instantaneous extinguishment of the burning tobacco.

Another object is to provide a cigarette snuffer, one end of which is open for the reception of a cigarette, while the other end is closed except for a small vent hole. This small hole allows smoke to be blown out of the cigarette in either direction while in the snuffer, thus cooling the cigarette, reducing drying of same, and freshening and avoiding the bad effect on taste and aroma incident to snuffing with a closed end snuffer. At the same time, this hole permits the venting of undesirable odors and allows continuous ventilation of the assembly, a thing which

avoids rapid accumulation of detrimental strong odors. This hole further facilitates cleaning the snuffer by blowing through the snuffer from the small hole end. Blowing in this manner is also a preferable way to remove short cigarettes which have slid completely into the snuffer under conditions of use.

Another object is to provide a snuffer which is small enough to be slipped into a cigarette package after removing at least two cigarettes therefrom, and is provided with means for resisting rolling when laid on a slightly inclined surface.

Another object is to provide a new method of snuffing a cigarette, and cooling and clearing same of smoke so as to facilitate a fresher taste and aroma when resmoked.

A further object is to provide an apparatus which makes possible economy of tobacco and paper without diminution of the amount of smoking done by the smoker.

A still further object is to provide a cigarette snuffer having a portion of its bore tapered so as to hold a cigarette from falling out after snuffing.

Still further objects and advantages of the present invention will become apparent as the description proceeds.

To the accomplishment of the foregoing and related ends, the invention, then, consists of the methods and means hereinafter fully described and particularly pointed out in the claims, the annexed drawing and the following description setting forth in detail certain means and modes of carrying out the invention, such disclosed means and modes illustrating, however, but several of the various ways in which the principle of the invention may be used.

In said annexed drawing:

40 Figure 1 shows a center longitudinal sectional view of one embodiment of the present invention.

Figure 2 shows a center longitudinal sectional view of another embodiment of the present invention wherein a portion of the bore of the snuffer is tapered.

Figure 3 shows a center longitudinal sectional view of still another embodiment of the present invention wherein the bottom of the bore of the snuffer slopes to a small vent opening.

50 Figure 4 shows a full top view of the snuffer illustrated in Figure 1.

Figure 5 shows a full bottom view of the snuffer illustrated in Figure 1.

55 Figure 6 shows a modified full bottom view of another embodiment of the present invention.

Referring more particularly to Figure 1 of the drawing, the device comprises a body member 1 provided with a suitable bore 2 preferably of a size slightly larger than the diameter of a cigarette so that same may be readily slid thereinto and yet the amount of air to support combustion will be held substantially at a minimum. The inlet end of the body member is preferably provided with an outward flare 3 to facilitate ease of insertion of a cigarette thereinto. The lower end of body member 1 is also provided with a small vent passageway 4 which facilitates inserting the cigarette, and cleaning the apparatus by blowing thereinto through the vent opening, as well as the removal of short cigarettes which have passed completely into the snuffer in the course of snuffing or carrying. Removal of the cigarette in this manner avoids injury to same and loss of tobacco incident to bumping the cigarette out of the snuffer. The passageway also facilitates ventilation of the apparatus with removal of stagnant smoke and odors.

The slipping of a lighted cigarette, burning end first, into the snuffer through the inlet end of same, almost instantaneously extinguishes same. Then by blowing through the cigarette, in either direction, the residual smoke contained by same will be removed so that it cannot adversely affect the taste and aroma of the cigarette. This blowing out, of course, is preferably conducted with the cigarette in the snuffer and same is facilitated due to the small passageway 4 in same.

The cigarette snuffer may have a substantially straight bore throughout as shown in Figure 1, although same is not absolutely necessary. For instance, as is shown in Figure 2, at least the lower portion, and preferably the half of the snuffer bore which extends to the vent end, may be provided with a moderate inward taper 5. This construction has the added advantage of lightly gripping the end portion of the cigarette dropped or pressed thereinto, a thing which facilitates carrying the cigarette in the snuffer and also prevents the cigarette from freely dropping out of the snuffer if the latter, with cigarette therein, is accidentally inverted. Tapering the bore of the snuffer also has the added advantage of still further reducing the air space in the snuffer with resultant even quicker snuffing of a cigarette placed therein.

The bottom of the snuffer may be provided with a sloping portion 6 which terminates at passageway 4 as is shown in Figure 3. This type of construction still further facilitates the blowing of ashes or the like from the bottom of the snuffer. The sloping portion 6 may be of various shapes, such as conical, variable taper, rounded, or the like, and the showing in Figure 3 is intended to diagrammatically illustrate all of these various forms. While the snuffer shown in Figure 3 has been illustrated with a straight bore, it is to be understood that the invention is not limited to that particular construction, since a tapered bore, combined tapered and straight bore, or the like, may be used in similar manner, and to simplify the showing, it is intended that Figure 3 is to be considered as diagrammatically showing same.

A rounded snuffer when laid on a slightly inclined surface, will tend to roll off of same. A simple way to reduce this rolling tendency is to provide the snuffer with a flat side 7 as is shown in Figures 4 and 5. Another way to accomplish this end involves the placing of one or more projecting members on the side of the snuffer. A

convenient way of doing the latter may be attained by placing a tack or tacks 8 in the side of the snuffer near its bottom. The projecting member or members may also be on a metal band placed around and fastened to the snuffer. Constructions of this general type are diagrammatically illustrated in Figure 6.

These snuffers may be made out of various materials, and preferably materials which, when fabricated as shown, will not readily ignite or be seriously injured due to the insertion of the burning end of a cigarette thereinto. Metal, wood, or some of the relatively non-inflammable plastics, may be used for this purpose. Wood is particularly suited for this use since it is easily obtainable and readily worked to shape.

After a lighted cigarette has been snuffed in the apparatus of the present invention, followed by blowing out of smoke contained in the cigarette and snuffer, the burned end of the cigarette will contain a substantial amount of charred tobacco which brings in the added advantage of adsorbing obnoxious odors caused by combustion or combustion refuse, thus again improving the taste and aroma of the cigarette when resmoked. While the present invention has been described in terms of snuffing cigarettes, it is to be understood that it is not limited to that, but rather it is adapted for use in snuffing cigars, et cetera, by merely varying the size of the snuffer to that required for the particular article to be snuffed.

Other modes of applying the principle of my invention may be employed instead of those explained, change being made as regards the means and the methods herein disclosed, provided those stated by any of the following claims or their equivalent be employed.

I therefore particularly point out and distinctly claim as my invention:

1. A method of the character described, which comprises quickly snuffing the burning end of an elongated body of tobacco by inserting the burning portion of same into a small compartment containing insufficient air to continuously support combustion, and then removing the free smoke from said tobacco by blowing through same in said compartment after the burning portion thereof has been extinguished therein.

2. A method of the character described, which comprises quickly snuffing the burning end of an elongated body of tobacco by inserting the burning end of said body into a small compartment closely fitting same and containing insufficient air to continuously support combustion, promptly removing the free smoke from said tobacco by forcing air through same toward the burned end thereof after extinguishing the burning end of same, and adsorbing at least a portion of the combustion odors in charcoal.

3. A method of the character described, which comprises quickly snuffing the burning end of an elongated body of tobacco by inserting the burning end of said body into a small compartment closely fitting same and containing insufficient air to continuously support combustion, promptly cooling and removing the free smoke from said tobacco by blowing air through said tobacco toward the burned end thereof after extinguishing the burning end of same, removing at least a portion of the combustion odors by means of charred tobacco, and ventilating said compartment and elongated body of tobacco therein while retarding the drying out of the tobacco within said compartment to an amount

less than the normal drying of said tobacco if freely exposed to ordinary room temperature and humidity.

4. A cigarette snuffer, which consists of a tubular member open at one end and provided with a small vent opening at the other, the open end of said tubular member being flared outward for ease of inserting a cigarette, the bore of said member being substantially cylindrical approximately one-half of its length and being of a size slightly larger than the diameter of a cigarette, the balance of said bore gradually tapering inward toward the vent opening end of the member, said taper being sufficient to facilitate the gripping of the inserted end of a cigarette 10 and the holding of same against free removal, 15

the outer surface of said tubular member being of roll-resisting construction.

5. An elongated tubular cigarette snuffer which has a body member with a flared opening at one end and a small vent opening at the other, the bore of said body member being substantially cylindrical approximately one-half of its length and being of a size slightly larger than the diameter of a cigarette, the balance of said bore of the body member gradually tapering inward toward the vent opening of the body member, said taper being sufficient to facilitate the gripping of the inserted end of the cigarette, and the holding of same against free removal.

WARD M. IRVIN.
